NAIL CLIPPER MERCHANTISING DISPLAY PACKAGE

Henry W. Bassett, South Britain, Conn. (% The W. E. Bassett Company, Roosevelt Drive, Derby, Conn.)

Filed Dec. 21, 1960, Ser. No. 63,292

Term of patent 14 years

(Cl. D58—2)

FIG. 1 is a front perspective view taken from the top and one side of a nail clipper merchandising display package embodying my new design; and

FIG. 2 is a longitudinal sectional view thereof taken on line 2—2 of FIG. 1.

The dominant features of my design reside in the full-line portions of the drawing.

I claim:

The ornamental design for a nail clipper merchandising display package, substantially as shown and described.
